AIR CONDITIONING APPARATUS INCLUDING
A STERILIZING MEANS

Lloyd M. Berryman, Baltimore, Md.

Application September 10, 1946, Serial No. 695,979

4 Claims. (Cl. 62—129)

1

This invention relates to air-conditioning equipment and more particularly to that branch thereof pertaining to the de-humidifying and sterilizing of air in structures.

A particular manner of de-humidifying air in an enclosed space consists in passing the ambient air at its normal temperature thru a cooling device where it is chilled to the dew point and the moisture thru condensation is deposited on fins or coils where it can accumulate and drain off into a tank or sewer. A refrigerating unit is employed for cooling the de-humidifying device. The disadvantage of this system lies in the fact that the refrigerating unit discharges the heat in a space separate from that being conditioned, or some medium such as flowing water is used to absorb and carry away the heat. This means that the temperatures and pressures must be considerably increased and it involves greater cost of operation as well as increased wear and tear than lower temperatures and pressures would induce. The space occupied is much greater and the installation requires the use of ducts, pipes or tubing to carry refrigerant and cooling air or water. The device is not portable, but is costly and inefficient. In addition no provision is usually made for sterilizing the processed air.

It is the purpose of the herein described invention to provide a new and improved air conditioning unit that will avoid one or more of the disadvantages and limitations of the prior art.

Another object of this invention is to provide a new and improved air conditioning unit that will de-hydrate air efficiently without changing the temperature to any great extent in the space to be de-hydrated.

Another object of this invention is to provide a new and improved air conditioning unit that will be compact, economical in original cost and operation and easily adapted for sterilizing purposes.

Still another object of the invention is to provide a new and improved air conditioning unit that will be fully portable and self contained.

A further object of the present invention comprises the method of reducing the temperature of dew laden air to the dew point, extracting the moisture by passing the air over a cooling coil, compressing the refrigerant, raising its temperature and pumping the refrigerant through a second set of coils where some of its heat is extracted by the cool de-humidified air as it passes over the second set of coils and raises the temperature of the de-humidified and sterilized air

2

back to its original temperature when it entered the apparatus.

A further object of the present invention is to make effective use of the transfer of heat from one part of the system to another, without materially increasing the size of the unit although increasing its capacity. It is understood that the term air-conditioning is used in a broad sense and includes de-humidifying of air as well as changing its temperatures.

For a clearer understanding of the invention reference is made to the appended drawings together with the following description, wherein a particular form of the invention is outlined, by way of example, to illustrate the principles and operation of the equipment involved, while the scope of the invention is emphasized in the claims.

The structure indicated in the drawings details the equipment used in this particular form and consists of various items in which:

Figure 1 is a plan view of an air-conditioning unit embodying this invention;

Figure 2 is a side elevation of Figure 1, with parts broken away to show its internal construction;

Figure 3 is a front view of Figure 1 looking in the direction of arrows 3—3, and

Figure 4 is a rear view of Figure 1 looking in the direction of arrows 4—4.

Similar reference numerals are used in the various drawings to designate similar parts.

The particular form of air-conditioning unit shown consists of a base 10 on which the parts are mounted and kept rigidly in the same relation to one another. On this base, a conventional type of compressor 11 operated by an electric motor 12 is assembled. The motor is located towards the middle of the base and longitudinally parallel to it. A fan 13 directly connected to a motor 14 is installed adjacent to the compressor motor 12. The fan itself is on the side of the motor 14 away from the motor 12, and has a propulsive action tending to pull air from in front of it, back towards the motor. In front

45 of the fan 13 a condenser 15 is positioned for receiving a gaseous coolant, like dichlorodifluoromethane as it leaves the compressor in a hot state, and after giving up this heat, liquefying the dichlorodifluoromethane passing therethrough. Its coils 16 are horizontally arranged and its outside frame 11 vertically supports them. An air space 18 is provided in front of this condenser and is enclosed by duct work or housing 19 that is held in place at one end of the condenser structure 15 and at the opposite end by

a de-hydrator 20. The de-hydrator is similar in general construction to the condenser, but is larger, and its coils 21 are formed with fins to collect the moisture from the air and carry it to a common drain piping 23, whence it passes to a tank for disposal. The housing 18 preferably encloses a sterilizing lamp 25 of the ultra-violet type directing its sterilizing rays across the area through which the air in the space 18 must travel. The air to be processed from the room passes first through the dehydrator 20, then through the space 18, activated by the rays of the lamp 25, thence through the condenser 15, and then back into the room again. The lamp 25 is suitably connected to, and controlled by, a circuit 41. During the last step, the treated air also passes over the motor 12 and compressor 11, but the effect of the air on the pieces of equipment is of little consequence. The arrangement for carrying the coolant dichlorodifluoromethane consists of a conducting pipe 26 connected at the compressor outlet 27, and containing dichlorodifluoromethane compressed to a pressure of about 80# p. s. i., and having a temperature of about 110° F. This induces a temperature of about 105° F. in the condenser 15, to which the pipe 26 is coupled at the inlet 28. As the coolant dichlorodifluoromethane passes through the condenser 15 it gives up its heat to the air which is forced through by the fan 13. The coolant dichlorodifluoromethane passes from the outlet 29 of the condenser 15, then through a second conducting piping 30 at room temperature and approaching liquid form and is deposited in a liquid receiver 33. The liquid is then conducted under pressure through pipe 31 to an expansion valve 35 and expanded into the de-hydrator 20 where the expansion of the coolant reduces the temperature to approximately 32° F. as it passes therethrough. The air from the room is drawn in at a normal temperature of about 70° F. and passes through the de-hydrator 20 where it is cooled by the dichlorodifluoromethane to about 35° F. and brought down to a dew point that makes it shed most of the moisture therein. This moisture is collected by the fins of the dehydrator 20 and carried off so it cannot contaminate the air again after it has passed through the dehydrator. The heat laden vapor is drawn from the de-hydrator 20 through the pipe 38 by the compressor 11, and is then passed through the process all over again. Thus in its action, the unit takes the air from the room at 70° F., cools it to 35° F., and de-hydrates it, then sterilizes it as it travels further through the unit, and then reheats it with the heat derived from the condenser and developed by the compression of the dichlorodifluoromethane in the compressor, while it is dry and passes it back into the room. Without this system of first cooling the warm air and de-hydrating it, and using it to cool the condenser structure, it would be necessary to cool the hot liquid by other means and thereby lose the advantage of conserving the power required to raise the temperature of the air back to room temperature. This would incidentally cause an increase in the compressor pressure. At the same time, the advantage of sterilizing the air when cooled is provided for in this invention and is understood to be very effective, since the bacteria are less active and lively, and the resistance to the rays of their physical lamp considerably lowered. The process permits a compact arrangement of the parts since they are aligned with one another and installed close

5 to each other to produce less losses in heat and effect. In other words, the further apart the parts are, the more access do they provide for the air currents induced by the heat to dissipate, and cool them. By keeping them close, the opposite effect occurs and the heat therein is used effectively in the work done by the invention.

10 While but one general form of the invention is shown in the drawings and described in the specifications, it is not desired to limit this application for patent to this particular form, as it is appreciated that other forms of construction could be made that would use the same principles and come within the scope of the appended claims.

15 Having thus described the invention, what is claimed is:

1. An air conditioning unit comprising in combination a compressor, a condenser coupled to said compressor, an expansion valve, a liquid receiver connected to one side of said expansion valve, a de-hydrator coupled to the other side of said expansion valve, a housing having its transverse center portion restricted into a conical form for enclosing the space between the condenser and de-hydrator for leading the de-hydrated air from the de-hydrator to the condenser where the temperature of the de-hydrated air is increased by the heat of said condenser, and a coolant compressed in said compressor and flowing primarily through said condenser to heat same and have its heat extracted by said cooled air flowing therethrough, said coolant being conducted from said condenser to said liquid receiver, then to the expansion valve where the coolant is expanded and passed through the dehydrator to absorb the heat and moisture from the incoming moist laden air.

2. An air conditioning unit comprising in combination a compressor, a condenser coupled to said compressor, a liquid receiver coupled to said condenser, an expansion valve coupled to said liquid receiver, a de-hydrator coupled to said expansion valve, a housing having its transverse center portion restricted into a conical form for enclosing the space between the condenser and de-hydrator for leading the de-hydrated air from the de-hydrator to the condenser where the temperature of the dehydrated air is increased by the heat of said condenser, and a coolant compressed in said compressor and flowing primarily through said condenser to heat same and have its heat extracted by said cooled air flowing therethrough, said coolant being conducted from said condenser to said liquid receiver, then to the expansion valve where the coolant is expanded and passed through the de-hydrator to absorb the heat and moisture from the incoming moist laden air, and means for sterilizing said treated air.

3. An air conditioning unit comprising in combination, a base, a dehydrator including a coolant therein mounted on said base adjacent one end thereof, adapted to cool air drawn therethrough and cause a deposit of moisture therein at the temperature it is cooled to, a converging housing to catch said air as it leaves the dehydrator, a sterilizing lamp in said housing to sterilize said air passing thereby and direct its rays therethrough, air moving means axially aligned with said housing for drawing said air through and propelling it over the said air moving means so as to extract heat therefrom and raise the temperature of the dehydrated air, a compressor for compressing said coolant as it

leaves the dehydrator after being raised in temperature in its reactions during the processing of the air during the cooling thereof as aforesaid, said compressor having some of its inherent heat absorbed by said air as it passes thereby, said compressor, housing, lamp, and dehydrator being aligned on said base on approximately the same axial line whereby the air flow will be in practically the same general direction as it passes by or through them.

4. An air conditioning unit comprising in combination, a base, a dehydrator including a coolant therein mounted on said base adjacent one end thereof, adapted to cool air drawn therethrough and cause a deposit of moisture therein at the temperature it is cooled to, a converging housing to catch said air as it leaves the dehydrator, a sterilizing lamp in said housing to sterilize said air passing thereby and direct its rays therethrough, air moving means axially aligned with said housing for drawing said air through and propelling it over the said air moving means so as to extract heat therefrom and raise the temperature of the dehydrated air, a compressor compressing said coolant as it leaves 25

the dehydrator after being raised in temperature in its reactions during the processing of the air during the cooling thereof as aforesaid, said operating means of the compression means having some of its inherent heat absorbed by said air as it passes thereby, said compressor, housing, lamp, and dehydrator being aligned on said base approximately on the same axis whereby the air flow will be in practically the same general direction as it passes by or through them, and a line of piping coupling the dehydrator and compressor together arranged to promote the conventional flow of coolant therebetween.
